UNITED STATES PATENT OFFICE.

JAMES H. HOWELL, OF MILL VALLEY, CALIFORNIA.

DESIGN FOR A CHILD'S VEHICLE.

57,229.

Specification for Design.

Patented Mar. 8, 1921.

Application filed April 22, 1919. Serial No. 291,989. Term of patent 3½ years.

To all whom it may concern:

Be it known that I, JAMES H. HOWELL, a citizen of the United States, and a resident of Mill Valley, county of Marin, State of California, have invented a new, original, and ornamental Design for a Child's Vehicle, of which the following is a specification, reference being had to the accompanying drawings, forming part thereof.

Figure 1 is a front view of the child's vehicle illustrating my new design.

Fig. 2 is a side view of the child's vehicle.

Fig. 3 is a plan view of the child's vehicle.

The airplane-like design of my invention is characterized by a narrow, elongated central body having flat parallel sides, and which inclines downwardly from its front end below which are parallel wheels of larger diameter than rear parallel wheels. The front end of the body is given greater height than the trailing portion and this higher part is about equal in length to the

width of superposed wing representing parts which are contiguous to the top and bottom edges of the fore-end of the body.

The airplane-like design is further simulated by a propeller disposed close to the front edges of the wings and body. A predominant feature is the rear, downward inclination of the body toward the rear wheels above which extends a seat, simulating the elevating rudder, and at the rear of the seat is a vertical blade representing the horizontal rudder.

The intermediate part of the body is free from projection, and the front wheels well spread and the rear wheels relatively close.

I claim:

The ornamental design for a child's vehicle, substantially as shown.

JAMES H. HOWELL.
